UNITED STATES PATENT OFFICE.

ADRIAN S. AILES, OF CHICAGO, ILLINOIS, ASSIGNOR OF SIXTY PER CENT. TO JOHN H. TAFT, OF CHICAGO, ILLINOIS.

AUXILIARY LOCK FOR SAFES, VAULTS, &c.

1,397,999.

Specification of Letters Patent.

Patented Nov. 22, 1921.

Application filed March 27, 1920. Serial No. 369,339.

To all whom it may concern:

Be it known that I, ADRIAN S. AILES, a citizen of the United States, residing at Chicago, in the county of Cook and State of Illinois, have invented a new and useful Improvement in Auxiliary Locks for Safes, Vaults, &c., of which the following is a specification.

This invention relates particularly to auxiliary locking devices for use in connection with the ordinary locking mechanism of safes and vaults.

The primary object of the invention is to provide an auxiliary lock of the improved construction and arrangement, which will provide greater safeguards than auxiliary locks heretofore known.

The invention is illustrated, in its preferred embodiment, in the accompanying drawings, in which—

Figure 1 represents a section in the wall of a safe having a door equipped with the usual locking mechanism and equipped also with the improved auxiliary locking mechanism, the view showing the inner side of the safe door; Fig. 2, a broken plan sectional view showing one of the auxiliary locks employed; Fig. 3, a vertical sectional view taken as indicated at line 3 of Fig. 2; Fig. 4, a broken sectional view taken as indicated at line 4 of Fig. 3; Fig. 5, a broken sectional view taken as indicated at line 5 of Fig. 3; and Fig. 6, a perspective view of a catch, or retainer, adapted to hold the dog, or catch, of the auxiliary locking device in retracted position after the bolt of the auxiliary locking device has been released from said dog and permitted to lock the safe.

In the illustration given, A represents the wall of a safe or vault; B, the door thereof; B', the ordinary locking mechanism of the safe; C and C', auxiliary locking devices which are normally inoperative; and C², a system of flexible connections connecting the auxiliary locking devices with the door B and serving to release the bolts of the auxiliary locking devices in the event that the main locking mechanism is tampered with.

The main locking mechanism B' comprises, in the illustration given, the horizontal bolts 1 which are connected with a vertical bar 2; and vertical bolts 3 operated by bell-crank levers 4 connected with the horizontal bolts. The bar 2 is adapted to be actuated by a horizontal bar 5 which is ac-

tuated from the combination box B² in the usual manner.

In the illustration given, each of the auxiliary locking devices C and C' comprises a tubular bolt-housing 6 having an open outer or front end screwed into a threaded perforation 6^a in a flange 7 with which the door is provided near the margin of its inner side; a bolt 8 provided near its rear end with a recess 8^a; a bolt-actuating spring 9 confined between the rear end of the bolt 8 and the closed rear end of the tubular member 6; a collar, or block, 10, secured on the bolt-housing 6, as by means of screws 10^a; a detent, catch, or dog, 11, mounted in a guide with which the collar 10 is provided and serving normally to hold the bolt 8 in retracted position; and a spring-actuated catch, or retainer, 12, adapted to hold the dog 11 in retracted position after it has been withdrawn from engagement with the bolt 8.

The dog, or detent, 11, is shown as comprising a small bolt disposed radially with respect to the main or locking bolt 8 of the auxiliary device, the inner end of the member 11 extending through a perforation 12^a in the member 12 and through a perforation in one side of the tubular member 6 and engaging the recess 8^a (shown as annular) of said bolt.

The bolt 8, when projected, is adapted to engage a recess in the wall A. In the illustration given in Fig. 2, this recess is disposed back of the flange 13; and the dotted lines 8 indicate the position of the bolt in the projected position. The collar 10 is provided, as shown in Fig. 5, with a perforation 14 which receives the tubular member 6; and the member 12, which is in the form of a thin strip, works between the tubular member 6 and the bore 14 in a longitudinal guide 15. In setting the device, the dog 11 is retracted against the force of the small spring 16 with which it is equipped, and the member 12 is retracted by a spring 12^b which is attached to the member 12 and to the tubular member 6. Thus, the inner end of the dog 11 will rest against the strip 12. The bolt 8 may then be forced in to compress the spring 9, after which the member 12 may be pushed inwardly to the position shown in Fig. 3, thus permitting the dog 11 to pass through the perforation 12^a and through the hole in the wall of the member 6 and into

engagement with the annular recess 8^a of the bolt 8.

Provision may be made for more securely anchoring or steadyng the tubular member 6, as illustrated in Figs. 2, 3, and 4. The means shown comprise a short bar, or cradle, 17, which is recessed at 17^a to engage the member 6. This bar is interposed between the member 6 and the door B. and is equipped near its ends with set-screws 18 which bear against the inner surface of the door. By adjusting these screws, the members 17 may be suitably positioned to afford a rest for the member 6, this being accomplished without the necessity of drilling holes in the door.

The system of the flexible connections C², in the illustration given, may be described as follows:

20 The dog, or radial plunger 11, of each auxiliary locking device is equipped with a ring 19. One of the auxiliary locking devices set above and the other below the combination box B². From each ring 19 extends a flexible connection, or steel wire, 20, which passes over a roller 21, through a guide 22, across the combination box, and is anchored to the door at the point 23. Also, connected to each ring 19 is a wire, or flexible member, 24, which passes through the pulley 21 and thence over a pulley 25 and connects with a spring 26 which is anchored to the door, as at 27. The springs 26 are normally held distended by wires, or flexible connections, 28 which are attached to the springs and pass about the pulleys 25, thence through guides 29 and then are connected with a rod, or turnbuckle, 30, disposed back of the combination box B², the turnbuckle 30 having connected therewith a wire 31 which is anchored to the door, as at 32. The wires 28 may be a single wire passing over the pulleys 25, through the guides 29, and through an eye 33 at one end of the turnbuckle. The wires 28 are put under strong tension by means of the turnbuckle, and normally hold the springs 26 against inaction, leaving the connections 24 slack.

If the combination be forced, as by means 50 of nitro-glycerin, the combination box B² will be forced inwardly and will exert tension on the wires 20, thus retracting the dogs, or radial plungers, 11, and permitting the springs 9 to force the bolts 8 of the auxiliary locking devices into engagement with the wall of the safe. If, on the other hand, a hole be cut in the door, as by means of an oxy-acetylene flame, this will result in cutting the wires 28 which anchor the 55 springs 26 normally against action, and this will permit the springs 26 to operate through the connections 24 to withdraw the dogs 11, thus permitting the auxiliary locking devices to automatically lock the door.

65 In practice, the auxiliary locking devices

are placed at various points on doors of different banking institutions, and the system is then covered by sheet-metal, so that the positions of the various parts are hidden. The manufacturer who installs the auxiliary locking devices, however, retains a diagram, or measurements, locating the auxiliary locking devices. Hence, the manufacturer who installs the devices is in position to send an expert to open the door in case of necessity. 70 This may be done by drilling a small hole at the appropriate point, inserting an instrument, and shoving the auxiliary locking bolt back. To enable this to be done, it is important that the dogs 11 shall not again 75 spring into position to prevent the retraction of the bolts 8. The desired object is accomplished by means of the spring-actuated retaining members 12, which are retracted and close the perforations in the walls of 80 the bolt-housing 6. This feature is also of advantage in preventing the inner ends of the dogs from interfering with the springs and in facilitating the work of inserting the 85 bolts 8 during the installation.

The device described, which serves to normally restrain the auxiliary bolt 8, is desirable for the reason that there is no danger of an improper assembly being effected in making the installation, and for the further reason that the device operates 95 purely to hold the auxiliary bolt 8 against accidental discharge. As pointed out, also, the device possesses advantages which facilitate the work of installation.

The foregoing detailed description has been given for clearness of understanding only, and no unnecessary limitation should be understood therefrom, but the appended 100 claims should be construed as broadly as permissible, in view of the prior art.

What I regard as new, and desire to secure by Letters Patent, is:

1. In combination, a safe provided with a door having a main locking mechanism, a normally inactive auxiliary locking device mounted on the door and arranged to lock the same closed independently of the main locking mechanism, a flexible connection controlling the auxiliary locking device and extending across the main locking mechanism and adapted to release the auxiliary lock when force is exerted upon said flexible member by abnormal movement of the main locking mechanism, a spring adapted to 110 effect release of the auxiliary locking device, and a flexible connection normally holding said spring against operation and extending across the main locking mechanism, whereby when said last-named flexible member is 115 severed the auxiliary locking device will be released and thrown to the locking position.

2. The combination with a door equipped with main locking mechanism, of auxiliary locking means comprising a normally-re-

- strained spring-pressed member adapted to operate when the main locking mechanism is tampered with, and means controlling the release of said spring-pressed member, comprising a normally taut flexible member controlling the release of said spring-pressed member and extending across the main locking mechanism and anchored, a normally inactive spring adapted to effect release of said spring-pressed member, and a flexible member normally restraining said spring from operation and associated with the main locking mechanism, whereby said first-named flexible connection will operate to release said spring-pressed member in case the main locking mechanism is moved abnormally and said second-named flexible connection will, when released or severed, permit said spring to effect release of said spring-pressed member.
3. In means of the character set forth, the combination with a door equipped with main locking mechanism, of auxiliary locking means comprising an auxiliary locking bolt, a spring tending to force said bolt to the locking position, a dog controlling said bolt, a spring adapted to effect release of said dog, and flexible connections associated with the main locking mechanism and including a connection adapted to release said dog when the main locking mechanism is moved abnormally and a connection which normally restrains said second-named spring from action and which, when itself released, permits said spring to retract said dog to allow said bolt to be projected.
4. In means of the character set forth, the combination with a door equipped with main locking mechanism, of auxiliary locking means comprising a tubular bolt-housing mounted on the door, a spring-pressed bolt in said housing, a member mounted on said housing, a spring-pressed dog mounted in said member and adapted to hold said bolt in retracted position, a spring-actuated retainer adapted to hold said dog in retracted position, and means connected with said dog and associated with the main locking mechanism, whereby when the main locking mechanism is tampered with said dog will be withdrawn and permit said bolt to be projected.
5. In means of the character set forth, the combination with a door equipped with main locking mechanism, of auxiliary locking means comprising a tubular bolt-housing mounted on said door, a spring-pressed bolt confined in said housing, a collar mounted on said tubular housing, a radial plunger mounted in said collar in a plane substantially at right angles to said tubular housing and adapted to hold said bolt in retracted position, and a flexible connection attached to said radial plunger and associated with the main locking mechanism, whereby the plunger will be retracted when the main locking mechanism is tampered with, thus permitting said bolt to be projected.
6. In means of the character set forth, the combination with a door equipped with main locking mechanism, of auxiliary locking means comprising a tubular bolt-housing mounted on said door, a spring-pressed bolt confined in said housing, a collar mounted on said tubular housing, a radial plunger mounted in said collar and adapted to hold said bolt in retracted position, a spring-actuated retainer adapted to hold said radial plunger in retracted position after the locking bolt has been projected, and a flexible connection attached to said plunger and associated with the main locking mechanism, whereby said plunger will be retracted when the main locking mechanism is tampered with.
7. In means of the character set forth, the combination with a door equipped with main locking mechanism, of auxiliary locking means comprising a tubular bolt-housing mounted on said door, a spring-pressed bolt confined in said housing, a collar mounted on said tubular housing, a radial plunger mounted in said collar adapted to hold said bolt in retracted position, means for retracting said radial plunger to permit said bolt to be projected, comprising a flexible connection adapted to be withdrawn by abnormal movement of the main locking mechanism, a normally inactive spring adapted to retract said radial plunger, and a flexible connection normally restraining said spring from action and adapted, when itself released, to release said spring and permit it to retract said radial plunger.

ADRIAN S. AILES.
